UNITED STATES PATENT OFFICE.

FREDERICK E. CRAIG, OF LAWRENCE, MASSACHUSETTS.

ELASTIC TIRE.

Application filed April 1, 1922. Serial No. 543,697.

To all whom it may concern:

Be it known that I, FREDERICK E. CRAIG, a citizen of the United States, residing at Lawrence, in the county of Essex and State of Massachusetts, have invented new and useful Improvements in Elastic Tires, of which the following is a specification.

This invention relates to an elastic tire, which includes an annular shoe or carcass 10 adapted to surround and be secured to a wheel rim, the shoe being of any suitable form and construction, whereby it is provided with a substantially tubular annular inner surface, which is interrupted by an 15 opening at the inner side of the shoe, through which a tubular cushioning member may be inserted. Said member is usually an inflatable inner tube.

The invention is embodied in a tire having 20 as its cushioning member a helical metal spring of resilient wire, instead of an inflatable inner tube, the form of said spring being such that it is adapted to creep longitudinally in contact with the inner surface 25 of the shoe, and resiliently support the tread without indenting the inner surface of the shoe and objectionably chafing and wearing away the said surface.

Of the accompanying drawings forming 30 a part of this specification,—

Figure 1 is a transverse section of a tire embodying the invention.

Figure 2 is a section on line 2—2 of Figure 1.

Figure 3 is a side view of a portion of the spring in its normal form, before it is flexed to form an annulus.

Figure 4 is a side view, showing the entire spring on a reduced scale.

40 The same reference characters indicate the same parts in all of the figures.

12 represents a tire shoe or carcass, which may be of any well known form, adapted to be secured to a rim, and to receive the 45 usual inflatable inner tube of a pneumatic tire, the inner surface of the shoe being substantially tubular, and interrupted by a mouth or opening 13 at the inner side of the shoe. Usually the body portion of the shoe 50 is made of alternating layers of fabric and rubber, and is provided with beaded edges, forming the sides of the opening 13, and with a tread layer 14, vulcanized to the body portion.

55 15 represents a helical spring, whose convolutions are formed to closely fit the inner

surface of the shoe, and bridge the opening 13 when the shoe is contracted and engaged with a rim. The spring is made of wire, which is square in cross section, and transversely flat at the exterior of the spring, so that the spring has a transversely flat external helical surface, formed by one of the sides of the wire, and constituting a helical runner, adapted to slide on the inner surface of the shoe. The length of the spring is such that it may be flexed and united at its ends to form an annulus of the same diameter as the interior of the shoe. The spring is free from positive engagement 60 with the shoe, so that it is adapted to creep circumferentially in the shoe.

The normal spacing of the convolutions when the spring is free, as shown by Figure 3, is such that when the spring is flexed to 65 form an annulus, the inner portions of the convolutions abut against each other, as shown at the lower portion of Figure 2, so that the inner portion of the periphery of the spring has a practically inner continuous face, adapted to slide or creep freely on the inner surface of the shoe. The convolutions diverge from the said inner face to form an outer face contacting with the tread portion of the shoe, and interrupted 70 by tapering spaces between the convolutions, of less width than the thickness of the wire. The separation of the arched outer portions of said convolutions from each other is so limited by the abutting together 75 of the inner portions, that the outer portions are also free to slide or creep on the inner surface of the shoe, the spaces between the said outer portions being narrower than the thickness of the wire, so that the material of the shoe cannot be indented by the convolutions and enter said spaces sufficiently to prevent the creeping of the spring, free creeping being permitted by said helical runner. It will be seen, therefore, that 80 the spring is adapted to cushion the shoe without objectionably chafing and wearing its inner surface, the creeping of the spring distributing the wear so that no grooves are 85 formed in the shoe by the spring.

The convolutions of the helix are practically radial to the center thereof. This radial arrangement not only causes the convolutions to exert their cushioning effect advantageously, but also maintains the 90 spaced apart portions of the transversely flat faces of the convolutions parallel with

the inner face of the shoe, as shown by Figure 2, so that each of the angular outer corners of each convolution has the same relation to the shoe as the other outer corner. The outer face of the helix, interrupted by the tapering spaces of less width than the thickness of the wire, is, therefore, adapted to slip on the shoe without obstruction to the slipping movement, which would be caused if one of the said outer corners projected outward farther than the other.

10 I prefer to make the spring of chromium vanadium steel wire. The size of the spring and the thickness of the wire will depend on the size of the shoe and the weight of the vehicle. The ends of the spring may be united by welding or otherwise, to form a continuous annular helix.

15 20 I claim:

In combination, a tire shoe or carcass adapted to be opened and contracted, and an annular cushioning member composed of square wire helically coiled, fixed, and

united at its ends to form a continuous annular helix in which the convolutions are substantially radial to the center of the annulus, are abutted together at their inner portions to form a practically continuous inner face, and diverge from said inner face to form an outer face contacting with the tread portion of the shoe, and interrupted by tapering spaces between the convolutions maintained by the abutting of the inner portions at less width than the thickness of the wire, whereby said outer face is prevented from indenting the inner face of the shoe, the transversely flat outer sides of the convolutions being maintained parallel with the inner face of the shoe by the radial arrangement of the convolutions, so that said sides collectively constitute a helical runner, adapted to creep on the inner face of the shoe, and thereby distribute wear.

30 35 40 45 In testimony whereof I have affixed my signature.

FREDERICK E. CRAIG.

Certificate of Correction.

It is hereby certified that in Letters Patent No. 1,470,913, granted October 16, 1923, upon the application of Frederick E. Craig, of Lawrence, Massachusetts, for an improvement in "Elastic Tires," an error appears in the printed specification requiring correction as follows: Page 2, line 24, in claim, for the word "fixed" read *flexed*; and that the said Letters Patent should be read with this correction therein that the same may conform to the record of the case in the Patent Office.

Signed and sealed this 6th day of November, A. D., 1923.

[SEAL.]

KARL FENNING,
Acting Commissioner of Patents.
